United States Patent Office

Des. 224,701
Patented Sept. 5, 1972

224,701

COMBINED BOTTLE AND CAP THEREFOR

Kent M. Wright, Sudbury, Mass., assignor to The Gillette Company, Boston, Mass.

Filed May 13, 1971, Ser. No. 143,289

Term of patent 14 years

Int. Cl. D9—01

U.S. Cl. D9—71

Fig. 1

Fig. 2

Fig. 3

Fig. 4

Fig. 5

FIG. 1 is a perspective view of a combined bottle and cap therefor showing my new design;

FIG. 2 is a top plan view thereof;

FIG. 3 is a side elevational view thereof;

FIG. 4 is a front elevational view thereof, and

FIG. 5 is a back elevational view thereof.

The undisclosed side is substantially a mirror image of the side shown.

I claim:

The ornamental design for a combined bottle and cap therefor, substantially as shown and described.
